(57) **CLAIM**

The ornamental design for a room divider, as shown and described.

DESCRIPTION

FIG. 1 is a front elevation view of the room divider according to the present invention; the rear elevation view is a mirror image hereof.

FIG. 2 is a front elevation view of the room divider, with the panels in an alternate position than that shown in FIG. 1.

FIG. 3 is a top view of the room divider shown in FIG. 1.

FIG. 4 is a bottom view of the room divider shown in FIG. 1; and,

FIG. 5 is a side view of the room divider shown in FIG. 1.
